CLAIM

The ornamental design for a television receiver, as shown and described.

DESCRIPTION

1. Television receiver
1.1 is a front perspective view of a television receiver showing the new design;
1.2 is a front view thereof;
1.3 is a back view thereof;
1.4 is a left side view thereof;
1.5 is a right side view thereof;
1.6 is a top view thereof;
1.7 is a bottom view thereof;
1.8 is a back perspective view thereof; and
1.9 is an enlarged view of a portion of FIG. 1.8.

The broken lines depict portions of the television receiver that form no part of the claimed design; the broken lines in reproduction 1.9 illustrate an example in-use environment showing a cable going through the hole at the back of the television receiver and forms no part of the claimed design; the dot-dashed lines indicate portions of the claimed design that are shown in the enlarged views, and form no part thereof.

This design is for a television receiver where the bottom rectangular frame can be used as a storage space.
